UNITED STATES PATENT OFFICE.

ELISHA NEWCOMB AND ERWIN B. NEWCOMB, OF CUMBERLAND MILLS, MAINE.

CAR-REPLACER.

SPECIFICATION forming part of Letters Patent No. 425,622, dated April 15, 1890.

Application filed January 2, 1890. Serial No. 335,651. (No model.)

To all whom it may concern:

Be it known that we, ELISHA NEWCOMB and ERWIN B. NEWCOMB, of Cumberland Mills, county of Cumberland, State of Maine, have 5 invented an Improvement in Car-Replacers, of which the following description, in connection with the accompanying drawings, is a specification, like letters on the drawings representing like parts.

10 Our invention relates to a car-replacer for facilitating the operation of replacing derailed wheels upon the track.

The invention is embodied in an apparatus comprising auxiliary rails arranged to be supported on the sleepers adjacent to the main rails of the track onto which the derailed wheels are to be lifted, the said auxiliary rails forming inclined planes that receive the treads of the derailed wheels, so that when 15 the car is pulled toward the said auxiliary rails the said wheels run up the inclined planes, and are raised thereby sufficiently high to pass onto the rails of the main track. The wheel that is between the rails of the main track need only be lifted far enough to bring the tread to the top of the main rail, while the wheel that is outside the track will have to be 20 lifted higher or raised sufficiently to bring the periphery of its flange to the top of the 25 main rail.

The apparatus comprises, in addition to the inclined planes or lifting-rails, a guide which co-operates with the lifting-rail between the tracks and acts upon the inner face of the 30 wheel at the back of its flange, the said guide-rail being inclined in the horizontal plane to the main track and acting to wedge or crowd the wheel toward the main-track rail, so that when the wheels are raised high enough to 35 come upon the main track they are crowded laterally by the guide into proper position upon the main track—that is, with the flanges of the pair of wheels between the main rails.

The invention consists, mainly, in details of 40 construction of the parts thus far described and their relations to one another, and to the means for fastening them upon the sleepers in proper relation to the main track.

For convenience the lifting-rail and guide, 45 which together act upon the derailed wheel that is between the rails of the main track, will be called a "frog," as it somewhat resem-

bles the frogs employed where two rails cross and intersect one another at an acute angle; and in accordance with this invention the 55 said frog-piece comprises a guide-piece which has a broad base to rest upon the sleepers, and also has projections that engage with the main rail, and at an intermediate point in its length is provided with a support for the 60 lifting-rail or inclined plane that co-operates with it. The said lifting-rail is preferably pivoted at an intermediate point on the guide-piece and may be turned so as to lie adjacent to either end of the guide-piece and between 65 the same and the main rail, so that the flange of the wheel to be replaced will come between the guide-piece and the lifting-rail, and the said lifting-rail will be between the flange of the wheel and the main rail and will raise the 70 tread of the wheel to the level of the main rail by the time that the guide, acting upon the inner face of the wheel, has crowded the outer face or edge of the wheel out to the main rail, which will then support the wheel- 75 tread as the latter passes off from the lifting-rail and is further acted upon by the guide to crowd the wheel over to its normal position on the track.

The part of the apparatus that acts upon 80 the wheel that is outside the rails of the main track is a reversible inclined plane having a suitable base to engage firmly with the sleepers and rising so high that the wheel, the tread of which runs up said inclined 85 plane, will have its flange raised to the top of the main rail by the time that the crowding action of the guide between the rails carries the said wheel laterally far enough to bring the flange on to the main rail, after 90 which it will run along with the flange of the wheel rolling on the main rail until the crowding action of the guide forces it over to the inside of the main rail, when the wheel will drop to its proper position on the track. 95

Figure 1 is a plan view of a car-wheel replacer embodying this invention in working position with relation to the main track and to the pair of wheels that are to be replaced, which are shown in dotted lines. Fig. 2 is a 100 side elevation of the frog-piece, as seen looking from the side toward the middle of the track; Fig. 3, a side elevation of the lifting-rail that acts on the wheel outside of the

main track; Fig. 4, a sectional detail on line x , Fig. 1, on a larger scale; and Fig. 5, a sectional detail on line y , Fig. 1.

The apparatus comprises a frog-piece A, that co-operates with the derailed wheel B between the main rails C D, and a lifting-rail E, that co-operates with the wheel B^2 , that is outside of the main rail D, the said frog-piece and lifting-rail being each of a length to span three sleepers of the track and be supported thereon and being placed each with one end upon the sleeper against which the derailed wheels come to rest. The frog-piece A comprises a guiding portion a , which may be a casting and has a foot or flange a^2 , which rests upon the sleepers and may be provided with spurs, as shown at a^3 , Fig. 2, to enter the sleepers and securely hold the said piece in position thereon. Midway of its length the said guide-piece is provided with a projection a^3 , (best shown in Fig. 5,) properly shaped to engage with the flange of the main rail C, as shown, and said projection is provided with a pin or pivot a^4 , upon which the lifting-rail b , which may also be a casting, is pivoted. Near each end the said guide-piece is provided with lateral projections a^5 a^6 , Fig. 1, also properly shaped to engage with the flange of the main rail C, and the said frog-piece is placed upon the sleeper with the middle projection a^3 and the end projection a^6 that is remote from the wheels to be replaced in engagement with the main rail C, thus bringing the said guide-piece at an angle to the said main rail, as shown, its end next the wheel to be replaced being at a greater distance from the main rail than the end remote from said wheel, and being such distance as to come within the inner face of the said wheel B or at the back of the flange thereof. Both ends of the guide-piece are alike, and it will be apparent that it can be set with either end nearest the main rail, as required in any particular case, according as it is placed at one or the other side of the wheel B or as it is needed at one or the other side of the main track. Before setting the guide-piece on the sleepers, as just described, the lifting-rail b , that is pivoted thereon, is turned to the end of the guide-piece toward the wheel to be replaced, and said lifting-rail then comes between the projection a^5 and the flange of the main rail, as best shown in Fig. 4, and may be securely fastened to the guide-piece a in any convenient manner. As shown in this instance, the said lifting-rail b is provided with a transverse opening b^2 , crossed by a vertical pin b^3 , which passes through a link b^4 , that can be brought over a stud or projection a^7 , fastened to the projection a^5 , as shown in Fig. 4. The upper face of the lifting-rail b near its pivoted end at the middle of the guide-piece is at a height nearly equal to or a trifle above the height of the main rail C, as shown in dotted lines, Fig. 5, and inclines downward from its pivoted end to the end that rests on the sleeper next the wheel to be

replaced, as clearly shown in Fig. 2, the said end being provided with a spur b^6 to engage with the sleeper. The upper face of said rail thus constitutes an inclined plane up which the tread of the wheel B rolls when pulled toward the frog-piece, and the space between the guide a and the main rail is such that the said guide crowds the wheel toward the main rail, and by the time that its tread is lifted by the rail b to the height of the main rail the outer edge of its tread will be crowded over to the main rail, so that by the time that the tread of the wheel has passed over and off from the lifting-rail b it will be received upon the main rail C, as clearly shown in Fig. 5, and in its further movement the guide will crowd it farther onto the main rail.

The lifting-rail E at the outside of the track may be a casting properly shaped, as shown in Figs. 1 and 3, to give sufficient strength with comparatively small weight, and it is provided with spurs e (see Fig. 3) to engage the sleepers, said rail also constituting an inclined plane similar in its action to the lifting-rail b , before explained, but higher, so that by the time the crowding action of the guide a has moved the wheel B^2 laterally far enough to bring its flange to the rail D, said wheel will have been lifted by the rail E high enough to bring the outer periphery of its flange to the top of the main rail, onto which it will pass by the crowding action of the guide a , which will continue until the flange of the wheel B^2 has been carried across the rail D and drops into place at the inside of said rail. The upper portion of the guide a projects above the level of the top of the lifting-rail b , as clearly shown in Figs. 4 and 5, so that, although it commonly acts upon the inner face of the wheel inside the flange, it will nevertheless act efficiently on an unflanged wheel, such as used on locomotives.

In order to support the guide a laterally while its wedging action is going on, it may be fastened or braced by connection with the adjacent rail or with the opposite rail, as preferred. As shown in this instance, the said guide is provided with transverse openings a^7 (see Fig. 2) at a short distance from its middle, through which the end of the brace-piece H passes, the said brace-piece having an offset or shoulder h , (see Fig. 5,) that bears against the guide a . The end of said brace-piece beyond the shoulder passes through the opening a^7 and engages the main rail C below its head, as shown at h^2 , Fig. 5, while the opposite end of the said brace is constructed, as shown at h^3 , Fig. 1, to engage with the opposite main rail D, and thus securely fasten the frog-piece.

We claim—

1. The combination of the guide-piece with the lifting-rail having one end pivotally connected with said guide-piece at the middle of its length, the said lifting-rail being movable on its pivot to a position adjacent to either end of said guide-piece, and the said guide-

piece projecting above the upper surface of the lifting-rail, substantially as and for the purpose described.

2. The combination of the lifting-rail adapted to be supported on the sleepers at the outside of the main rail and forming an inclined plane which receives the tread of the wheel and raises the said wheel until its flange is brought above the top of the main rail, with the frog adapted to be supported between the rails, said frog comprising a guide-piece that acts on the inner face of the wheel, and a lifting-rail connected with the said guide-piece, the said guide extending higher than the said lifting-rail, whereby it may act upon an unflanged wheel, substantially as described.

3. The guide-piece provided with a lateral projection at its middle point and one near each end adapted to engage with the main rail, the middle projection extending farther than the end ones, combined with a lifting-rail connected with the middle projection of the said guide-piece and adapted to engage with one of the end projections thereof between it and the main rail, while the other end projection is engaged with the main rail, substantially as described.

4. The guide-piece provided with a lateral projection at its middle point and one near each end adapted to engage with the main rail, combined with a lifting-rail connected with the middle projection of said guide-piece and adapted to engage with one of the end projections thereof, and a fastening by which said lifting-rail is connected with said end projection of the guide-piece, substantially as described.

5. The guide-piece and lifting-rail pivotally connected at one end with the middle of said guide-piece, said guide-piece having transverse openings, combined with a brace having a projection that passes through one of the said openings of the guide-piece and a shoulder that engages said guide-piece at the side of the openings, substantially as and for the purpose described.

In testimony whereof we have signed our names to this specification in the presence of two subscribing witnesses.
